DRAIN STOPPER

Robert L. Behre, Beverly Hills, Calif.

Application January 8, 1945, Serial No. 571,743

4 Claims. (Cl. 4—293)

1

This invention relates to stoppers, and more particularly to a stopper for utilization in closing drain openings and which provides a strainer therefor.

In sinks, basins, laundry trays, etc., it is common practice to provide a drain opening leading to a trap or the like and through which the sink, basin, or tray may be drained. In order to provide a stopping element for such trays, basins or sinks, it has been common to utilize a disc of rubber or similar flexible material which, when placed over the drain, will provide a stopper element therefor preventing the draining thereof. When, however, such rubber disc is removed from the position of closing the drain, the drain is fully opened permitting the entire contents of the said sink, basin or tray to pass through the opening. The ultimate result of such operation is to clog the trap or drain pipes necessitating their removal and cleaning out.

It is therefore an object of this invention to provide a stopper which may be utilized for effectively closing such drains but which also incorporates therein means for straining the water as it is allowed to pass through the drain opening.

Another object of this invention is to provide a convenient and flexible form of drain closure adapted for closing a drain opening of a sink, basin or tray and which has incorporated therein a straining element and the means for closing the drain passage through the straining element and which is particularly applicable for use in connection with closing drain openings and at the same time may be utilized for straining the water to remove foreign matter contained therein preventing the same from passing through the drain and which may then be easily removed from position within the sink, basin or tray, together with the matter that has been strained from the water during the draining process.

Other objects and advantages of this invention it is believed will be apparent from the following detailed description of a preferred embodiment thereof as illustrated in the accompanying drawings.

In the drawings:

Figure 1 is a top plan view of a drain stopper embodying my invention.

Figure 2 is a view similar to Figure 1 illustrating the strainer-stopper element removed therefrom.

Figure 3 is a top plan view of the strainer-stopper removed from Figure 1.

Figure 4 is a sectional elevation of a drain stopper embodying my invention as illustrating

2

the same in position over the drain opening of a sink, basin or tray.

Figure 5 is a side elevation of a modified form of drain stopper embodying my invention.

5 Figure 6 is a plan view of the strainer element embodied in the modification of Figure 5.

In the drawings I have illustrated the drain stopper embodying my invention as adapted for closing a drain 1 formed in the bottom 2 of a basin, sink or tray. The drain opening 1 is established through a flanged sleeve 3, the cylindrical extension of which is passed through the opening formed in the bottom 2 and is held in position by means of a lock ring 4 engaging a sealing ring 5. A drain pipe 6 is positioned within the member 3 and ordinarily leads to a trap (not shown).

The drain embodying my invention includes a disc stopper 7 which may be formed of rubber, 20 plastic or other suitable material which is of a diameter greater than the drain opening 2 formed in the bottom of the basin, sink or tray so as to lie flat upon the surface thereof at its periphery, the weight of the water acting to hold the said disc against the bottom 2 so as to form therewith a fluid-tight connection. The upper surface 8 of the disc 7 is preferably tapered toward the outer periphery so that the disc is relatively thin at its outer edge 9. Within the center of the disc 30 7 there is formed a drain passage 10 in which a suitable form of strainer or screen is mounted.

In the form of my invention illustrated in Figures 1 to 4, inclusive, the strainer is formed by carrying a web 11 of the material of the stopper across the opening 10 and forming this web with a multiplicity of strainer apertures 12 of suitable size to strain the water as it passes into the drain opening 1. The passage 10 is closed by a disc 13 which may likewise be formed of 40 rubber, plastic or other suitable material and seats upon an annular shoulder 14 formed by the extension of the web 11 across the opening 10. In this manner the disc 13 seats within a recess formed in the upper surface of the stopper disc 7. As illustrated, both the stopper disc 7 and the closure disc 13 may be provided with vertical projections or knobs 15 by which they may be lifted from their positions.

The mode of operation of this structure is 50 that it is placed in the sink basin or tray over the drain opening 1 and the water used for washing dishes, clothes, or the like, is admitted to the basin, tray or sink, and the washing operation is carried out, the stopper disc 7, together with 55 the closure disc 13, operating to prevent the water

from passing through the drain opening 1. After the washing operation has been completed, the closure disc 13 is removed, leaving the stopper disc 7 in position. The water then drains through the drain openings 12 and all foreign matter remaining in the water collects within the recess formed in the stopper disc 7 upon the surface of the web 11. When the water is completely drained through the opening 1, the foreign matter which otherwise would have been passed through the drain opening 1 and into the trap may be then removed from the basin, sink or tray by lifting upon the drain stopper disc 7, thereby removing the foreign matter from within the basin, sink or tray. This foreign matter may be then removed by shaking the same over a suitable disposal can without requiring the operator to collect the material in her fingers.

The modification illustrated in Figure 5 is substantially similar to that illustrated in Figures 1 to 4, inclusive, except in this modification the passage 10a formed in the stopper disc 7a has mounted therein a metallic screen 12a and this screen may be molded or suitably held within the passage as desired. As illustrated, the screen is removable and is mounted upon an annular shoulder 11a, formed by projecting this annular shoulder into the passage 10a. The closure disc 13a is mounted within the recess formed in the stopper disc 7a within the passage 10a and may then rest upon the screen 12a. In other respects this modification is substantially similar both in structure and mode of operation to that set forth in connection with the modification illustrated in Figures 1 to 4, inclusive.

Having fully described my invention, it is to be understood that I do not wish to be limited to the details herein set forth, but my invention is of the full scope of the appended claims.

I claim:

1. A drain stopper including a flexible substantially flat disc adapted to be removably supported over a drain opening in a sink, basin or tray, and the disc having a greater diameter than the opening so as to be supported upon the bottom of the said sink, basin or tray over the said opening and form a seal therewith, the drain stopper having a central passage formed there-

through, strainer means positioned in the passage, a central recess formed in the stopper disc above the strainer means, and a closure disc removably supported in said recess on the strainer means acting to normally close the passage.

2. In a drain stopper, the combination of a flexible substantially flat disc of relatively thin material having a central passage formed therethrough, the disc having a substantially greater diameter than the central passage and being adapted to rest on the bottom of a sink, basin or tray to form a seal therewith, the material of said disc being extended as a web across the passage and having drain openings formed therein, the passage defining a recess above the web, and a stopper disc removably mounted in the recess.

3. A drain stopper consisting of a substantially flat flexible disc of rubber having a central drain passage formed therein, the disc having a substantially greater diameter than the central passage and being adapted to rest on the bottom of a sink, basin or tray to form a seal therewith, a straining screen mounted in the passage below the upper surface of the stopper disc to define a recess within the passage, and a closure disc removably mounted in said recess.

4. A drain stopper comprising a substantially flat rubber disc having a central drain passage formed therein, the disc having a substantially greater diameter than the central passage and being adapted to rest on the bottom of a sink, basin or tray to form a seal therewith, strainer means positioned in the passage below the upper surface of the stopper to define a recess within the passage, and a closure disc removably mounted in said recess.
